UNITED STATES PATENT OFFICE.

FRANK E. SNOW, OF CHICAGO, ILLINOIS, ASSIGNOR TO JENNIE E. LAWSON,
OF SAME PLACE.

DESIGN FOR A LAMP-CASE.

SPECIFICATION forming part of Design No. 28,595, dated May 10, 1898.

Application filed October 8, 1897. Serial No. 654,592. Term of patent 3½ years.

To all whom it may concern:

Be it known that I, FRANK E. SNOW, a citizen of the United States, residing at Chicago, in the county of Cook and State of Illinois, have invented and produced a new and original Design for a Lamp-Case, of which the following is a specification, reference being had to the accompanying drawings, forming a part thereof.

10 Figure 1 is a side of a lamp-case, showing my design; and Fig. 2, a front elevation of same, looking in the direction indicated by arrow 4, Fig. 1. Fig. 3 is a rear elevation looking in the direction opposite that indicated by arrow 4, Fig. 1.

15 The principal features comprising the unitary design of my new lamp-case consist of the main body portion A, which is of spherical shape, the portion B, which has the form

of a truncated cone and whose small end 20 joins one side of the spherical main body portion, and the portion C, which is the segment of a sphere and which forms the outer end termination of the large end of the truncated cone-shaped portion B, as shown. 25

What I claim is—

A design for a lamp-case, consisting of a sphere having a truncated cone mounted at one side and flaring outwardly, and terminating in the segment of a sphere, as shown 30 and described.

In testimony that I claim the foregoing I have hereunto set my hand, this 7th day of August, 1897, in the presence of witnesses.

FRANK E. SNOW.

Witnesses:

OSCAR SNELL,
LAURA E. CLARKE.
